UNITED STATES PATENT OFFICE

JOSEPH W. KEFFER, OF CHICAGO, ILLINOIS

CLAMP

Application filed October 26, 1927. Serial No. 228,806.

This invention relates to a clamp for concrete forms, of the general type shown in my prior Patent No. 1,590,033, dated June 22, 1926, and is in the nature of an improvement 5 on my said patent.

The principal object of the invention is to provide generally improved and more efficient bearing blocks for use at the crossing point of two clamping members to hold these 10 members together and to exert the necessary force on them in order to tighten the clamp and retain it in tightened position.

It is another object of the invention to design these bearing blocks so that either side 15 of one block may be brought into contact with the appropriate bearing surface of another block, thus permitting the clamping members to be applied equally effectively upside down as right side up, and eliminating 20 the delays heretofore incident to reversing clamping members which had been applied hastily in the wrong position.

A further object of the invention is to shape the bearing blocks in such a way that 25 either one of the clamping members, where they cross each other, may be placed on top of the other, it thus being unnecessary to see that a given one of the members is always placed uppermost, as heretofore.

With these and other ends in view, the invention comprises the structure and combination of parts which will appear more clearly from the following description when read 35 in conjunction with the accompanying drawings, the novel features being pointed out in the claims following the description.

In the drawings:

Figure 1 is a horizontal section through a form for a concrete column with a clamp 40 applied thereto, showing one possible embodiment of the invention in plan;

Figure 2 is a side elevation of the parts shown in Figure 1;

Figure 3 is a vertical section taken approximately along the line 3—3 of Figure 1;

Figure 4 is a plan of one possible embodiment of a bearing block;

Figure 5 is a side elevation of the same;

Figure 6 is an end elevation of the same, 50 and

Figure 7 is a perspective view of the same.

In Figure 1 of the drawings, there is illustrated a conventional form for a rectangular concrete column, this form consisting of planks or other suitable members comprising the four walls 11. In order to hold these walls in position while the concrete is being poured and while it is setting, clamps are ordinarily placed around the walls of the form at intervals throughout the length of the column, these clamps being of such a nature that they do not injure the material of which the form is constructed. Hence, when the concrete has set, the clamps may be removed for use elsewhere, and the walls of the form may likewise be taken down, to be reassembled into a form for another column.

The clamp here shown comprises two pairs of members, the two members of each pair being pivotally connected to each other. As is illustrated in Figure 1, the two members 12 and 13, extending along two sides of the form, are pivoted at 14 to each other, and the members 15 and 16, constituting the other pair and extending along the other two sides of the form, are similarly pivoted at 17. It is seen from Figure 1 that one member of each pair crosses one of the members of the other pair. Clamping members pivoted to each other as described above are well known and widely used, being shown, for instance, in my prior patent above identified.

Slidably-mounted on each of the clamping members 12, 13, 15 and 16 is what may be termed a bearing block, these blocks all being similar to each other and being designated respectively by the numerals 18, 19, 20 and 21, in Figure 1. The cooperation between suitable bearing surfaces on two adjacent bearing blocks serves to retain the clamping members in their tightened position, and movement of the blocks along the clamping members, in the manner described below, results in tightening the clamp. These bearing blocks 18, 19, 20 and 21 correspond in a general way to the blocks 28 shown in my said prior patent, but are greatly improved over those shown in the patent, and the use of these new blocks results in a much more efficient 100

and flexible clamp than any heretofore known.

The detailed construction of each of the bearing blocks may be best understood from reference to Figures 3 to 7 inclusive, from which it is seen that each block has a top wall 25, bottom wall 26, and side walls 27 and 28, so connected as to leave a rectangular passageway, open at both ends, through the block. 10 This passageway is of such a size that the blocks may slide easily along the clamping members, such as 12 and 13, one block being mounted on each of the clamping members, as shown in Figure 1.

15 Slots 30 are formed through the top and bottom walls 25 and 26 of the bearing blocks, and slots 31 through the clamping members 12, 13, 15 and 16. Wedges 32 may be inserted through these slots, as shown particularly in Figure 3, and may thus be used to move the bearing blocks relative to the clamping members. The spacing of the slots 31 in the members is somewhat different than the spacing of the slots 30 in the blocks, so that there will 25 always be one slot in the clamping member aligned with a slot in the block, thus allowing a wedge to be inserted through the slots no matter in what position the block may be on the clamping member.

30 At one end of the passageway through the bearing block, wing walls 40 and 41 are formed, extending obliquely outwardly and rearwardly from two opposite edges of the passageway, as shown especially in Figures 35 4 and 7. These wing walls form bearing surfaces, either one of which is adapted to cooperate with one of the wing walls on the second bearing block, mounted on the clamping member which crosses the member on which the first block is mounted. It is the 40 coaction of the bearing surfaces on the two blocks, when the blocks are moved along the clamping members by the action of the wedges, that tightens the clamp and holds it in proper position. It will be readily apparent, from an inspection of Figure 1 that as either of the blocks is moved forward, the 45 reaction between the two bearing surfaces will produce, in each of the blocks, a force 50 component tending to draw the clamping member lengthwise, and another component tending to move the clamping member sideways against the sides of the form. Thus the clamp is tightened, and is held tight as long 55 as the wedges remain in place. To loosen the clamp for removal, it is necessary only to take out the wedges and slide the bearing blocks back, in a direction away from the corners of the form.

60 Heretofore, the bearing blocks have been made with only one bearing surface on each block. This has made it necessary to exercise great care in applying the clamping members to the form, because they would cooperate with each other only in one relative

position, and could not be reversed. It has been found that in the hurry and rush incident to actual use, the clamping members have often been placed in reverse position, and it has been necessary to change them before the clamp could be tightened. 70

In the present construction, however, the provision of two bearing surfaces, one on each side of the block, obviates this difficulty, and permits the clamping members to be used in any way. If a clamping member be turned one side up, one of the two oblique surfaces on its block will cooperate with surfaces on the other block, and if it be turned the other side up, the other oblique surface will serve 75 just as effectively in accomplishing the desired purpose.

This reversibility of the clamping members and bearing blocks is illustrated in Figure 1, where it is seen that the members 12 and 13 and the blocks 18 and 19 are one side up, while the other members 15 and 16, and their blocks 20 and 21, are the other side up. 80

To hold the two pairs of clamping members in contact with each other where they cross, so that they will not become separated vertically, various means may be employed. In the embodiment here shown, one end of the passageway in each block has walls 45 extending outwardly from the two opposite edges thereof from which the wing walls 40 and 41 do not extend. These walls 45 lie in a plane substantially perpendicular to the longitudinal axis of the passageway and each wall extends away from the edge of the passageway for a distance approximately equal to the thickness of the passageway, and terminates in a supporting lug 46 which projects forwardly from the walls 45, as shown 95 particularly in Figures 3, 5 and 7.

From the statements above made, it will be apparent that the distance from one of the lugs 46 to the other will be approximately three times the thickness of the passageway through the bearing block. 100

When two of the clamping members cross each other, one member is received in the space between the other member and one of the supporting lugs 46 of the bearing block mounted on this other member. This is illustrated particularly in Figure 3, where it is seen that one of the clamping members such as 15 crosses below the other member such as 13 and fits in the space between the bottom surface of the other member 13 and the top surface of the lower lug 46 on the bearing block which is mounted on 13. This lug 46 therefore serves to support the clamping member 15 and holds the two members 13 and 15 from becoming separated vertically. 115 At the same time, the upper supporting lug 46 on the other bearing block mounted on the member 15 will overlie the clamping member 13 so that it also will prevent vertical separation of the two members. 120

In the bearing blocks heretofore known, such as those shown in my prior patent, only one space was provided for receiving the crossed member in the bearing block, and therefore for this reason also, as well as on account of the provision of only one bearing surface, it was necessary to apply the clamping members always in one position, so that they were non-reversible. In the construction here shown, however, the two supporting lugs 46 are provided one above and one below the clamping member, so that the other clamping member may be received either above or below the first member, and this makes a device reversible.

The operation of this clamping mechanism may be briefly described as follows. After the boards constituting the sides of the concrete column form are set in place, two pairs of clamping members are placed against the sides of the form, with the pivoted corners of the clamping members at opposite corners of the form, as shown in Figure 1. Due to the reversible construction of the bearing blocks mounted on these clamping members, either of the pairs of clamping members may be turned either side up, and it is wholly unnecessary for the workmen to take time in determining which side must be placed uppermost. The clamping members are then held in a position such as indicated in Figure 1, and the bearing blocks are slid along the clamping members until the two bearing surfaces come into contact with each other. The wedges are then inserted through proper slots in the bearing blocks and clamping members and by driving the wedges, the clamp may be tightened to any desired degree. Any of the clamping members may be crossed either above or below the other clamping member which crosses it, since space is provided in each bearing block for receiving the crossed member either between the top supporting lug 46 and the top surface of the member on which the bearing block is mounted, or between the bottom supporting lug 46 and the bottom surface of the member.

It should be understood that clamps of this type are portable articles, carried from point to point on one construction job, and from one job to another. In the frequent handling to which these articles are subjected, the small parts, such as the wedges and bearing blocks, are apt to become lost, thus causing considerable inconvenience and waste of time. To obviate this, the clamping members, bearing blocks, and wedges are preferably secured to each other in such a way that they can not become separated. In the embodiment here shown, stop members such as 35 may be placed near the ends of the clamping members so as to prevent the bearing blocks from being removed from the members. The wedges 32 may be attached to the bearing blocks by means of flexible members

such as the chains 36 fastened at one end to the wedges and at the other to eyelets 37 formed on the bearing blocks.

While one embodiment of the invention has been disclosed, it is to be understood that the inventive idea may be carried out in a number of ways. This application is therefore not to be limited to the precise details shown, but is intended to cover all modifications thereof falling within the spirit of the invention or the scope of the appended claims.

I claim:

1. A clamp comprising, in combination, a plurality of clamping members, adapted to cross each other and a bearing block slidably mounted on each of said clamping members, each of said bearing blocks having oblique bearing surfaces on opposite sides thereof, either of said surfaces being adapted to cooperate with a bearing surface on a block on the other clamping member so as to hold said clamping bars in clamping position.

2. A clamp comprising, in combination, a plurality of clamping members, adapted to cross each other, and a bearing block slidably mounted on each of said clamping members, each of said bearing blocks having a lug spaced above the clamping member on which said bearing block is mounted and a second lug spaced below said clamping member, so that the clamping member which crosses said member on which the block is mounted may be received in the space between the lug and the member either above or below the latter.

3. A clamp comprising, in combination, a plurality of clamping members, adapted to cross each other, and a bearing block slidably mounted on each of said clamping members, each of said bearing blocks having oblique bearing surfaces on opposite sides thereof, either of said surfaces being adapted to cooperate with a bearing surface on a block on the other clamping member so as to hold said clamping bars in clamping position, and each of said bearing blocks also having a lug spaced above the clamping member on which said bearing block is mounted and a second lug spaced below said clamping member, so that the clamping member which crosses said member on which the block is mounted may be received in the space between the lug and the member either above or below the latter.

4. A clamp comprising, in combination, two members crossing each other at an angle, and a bearing block slidably mounted on each of said members, a bearing surface on each of said bearing blocks adapted to cooperate with a bearing surface on the other block, and a plurality of supporting lugs on each of said bearing blocks, one of said supporting lugs on a bearing block mounted on one of said two members being adapted to overlie the second member when said second member crosses above said first member, and another of said lugs being adapted to underlie said

second member when said second member crosses below said first member.

5. A clamp comprising, in combination, two members crossing each other at an angle, and a bearing block slidably mounted on each 5 of said members, a bearing surface on each of said bearing blocks adapted to cooperate with a bearing surface on the other block, and means on each block forming a channel both above and below the member on which the 10 block is mounted, either of said channels being capable of receiving the other of said two crossed members.

6. A bearing block for use in a clamping mechanism, said block comprising, in combination, walls forming a passageway of rectangular cross section, and an oblique flange attached to each of two opposite walls of said passageway so as to form bearing surfaces at approximately 45° to the axis of said passageway.

7. A bearing block for use in a clamping mechanism, said block comprising, in combination, walls forming a passageway of rectangular cross section, and lugs attached to 25 each of two opposite walls of said passageway at one end thereof and offset from the sides of said passageway a distance approximately equal to the thickness of said passageway, so that said lugs form between them a channel 30 having a thickness approximately three times that of said passageway.

8. A bearing block for use in a clamping mechanism, said block comprising, in combination, walls forming a passageway of rectangular cross section open at both ends, wing walls extending outwardly from two opposite sides of said passageway at one end thereof so as to form oblique bearing surfaces, walls 35 at the other two opposite sides of said passageway, each extending outwardly from the edge of the passageway for a distance substantially equal to the thickness of said passageway, and forwardly extending lugs at the outer edges of each of said lateral walls.

45 In witness whereof, I have hereunto signed my name.

JOSEPH W. KEFFER.
